UNITED STATES PATENT OFFICE.

DANIEL B. STAUFF, OF UNIONTOWN, PENNSYLVANIA.

COAL-LOADER.

1,246,673.

Specification of Letters Patent. Patented Nov. 13, 1917.

Application filed January 6, 1917. Serial No. 140,910.

To all whom it may concern:

Be it known that I, DANIEL B. STAUFF, a citizen of the United States, and a resident of Uniontown, in the county of Fayette and State of Pennsylvania, have invented a new and Improved Coal-Loader, of which the following is a full, clear, and exact description.

This invention relates to coal handling devices or the like and has particular reference to mechanical means for gathering and conveying coal from the ground and delivering it into mine cars or the like.

Among the objects of the invention is to provide a machine of a substantially self-contained nature or one which carries its own power devices, the same being designed particularly for operation in coal mines where the amount of head and side room is comparatively limited or restricted.

Another object of the invention is to provide a coal gathering, conveying or loading machine which is mounted upon a railway truck and so constructed that it may be positioned and inclined for the purpose of gathering the coal from a low level, as the bottom of the mine, and conveyance thereof to a higher position for dumping into a mine car or flat car, and at the same time providing for the tilting of the main parts of the machine around an intermediate horizontal axis, so as to facilitate the transportation thereof along the tram car tracks and around comparatively sharp curves or angles.

A still further object is to provide a coal-handling machine having a comparatively broad receiving mouth or pan so as to gather coal from both sides of the track as well as along the center thereof, such pan construction, however, being provided with lateral wings or sections hinged along lines parallel to the direction of movement of the machine or truck, thus facilitating the folding of the machine into a comparatively narrow compass for transportation purposes when out of use.

A still further object of this invention is to provide a coal-handling machine mounted upon a truck carrying the prime mover, through the operation of which the gathering and conveying portions of the machine are operated and also through which the truck and machine as a whole may be progressed forcibly forward at a low speed co-

incidently with the gathering and delivery of coal.

While I refer in this specification to coal as the medium to be handled, I wish it to be understood that the field of usefulness for the machine is not to be so limited in practice, inasmuch as it is adapted for the handling of gravel, ballast, broken stone, snow, ice, grain or various other commodities. I wish to observe also that the details of construction of the machine are subject to a wide range of variation without departing from the spirit of the invention and that the several parts may be made of any suitable materials within the judgment of the construction engineer.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a plan view showing the machine in operative position;

Fig. 2 is a side elevation of the same; 85

Fig. 3 is a side elevation of the machine tilted or adjusted for transportation;

Fig. 4 is a vertical longitudinal section indicating the gathering means in operative position, the section being on the broken line 4-4 of Fig. 1;

Fig. 5 is a front elevation of the machine with the conveyer tilted to approximately horizontal position, as indicated in Fig. 3, but preliminary to the tilting of the gathering means to the position of Fig. 3;

Fig. 6 is a fragmentary view of one end of the gathering pan showing one of the foldable wings and the relation of the driving mechanism for the feeder wheels thereto; and

Fig. 7 is a detail view of the main drive shaft and parts associated therewith.

In the practical adaptation of this machine, I show a truck comprising a frame 10 supported upon the wheels 11 adapted to be rolled upon track rails 12 or the like. The frame 10 is shown supplied with a motor M of any convenient type, of which 13 indicates the main driving shaft.

Any suitable means may be provided to propel the truck in either direction along the track. The means I show for propelling the same forwardly along the direction of excavation or gathering of the coal includes a pair of spools 14 secured upon a shaft journaled transversely across the frame in or adjacent to the motor casing and driven at low speed through any suitable intermediate gearing 16 from the motor shaft 13. A pair of cables 17 are secured to the respective spools 14 and have their other ends anchored as at 18 to posts or other fixed objects along the trackway. The spool shaft 15 may be thrown in or out of gear with the motor devices by means of a clutch 19 of any suitable construction.

This machine includes a conveyer comprising a frame 20 constructed of channel beams or the like and having a bottom panel 21 over which the coal is dragged or conveyed by the endless conveyer belt, shown as comprising an endless series of flights 22 secured to sprocket chains 23. For the convenience of transportation, the conveyer frame is preferably jointed intermediate of its ends, as indicated at 24, providing an auxiliary section 25, the head wheel 26 of which is provided with tension means 27 of any suitable or well known construction in the conveyer art. A hand-operated windlass 28 is carried upon the rear end of the main section of the conveyer frame and by means of cables 29 anchored at their outer ends to the auxiliary section or a chute 30 secured thereto, the auxiliary section and chute are swung into operative position. The middle portion of the conveyer frame is suitably stiffened or reinforced and swung upon a transverse axis. The side bars of the conveyer frame are mounted tiltably upon oppositely alined thimbles 31 fixed upon pedestals 32 on the truck frame. These thimbles provide bearings for the main drive shaft 33 which extends through the thimbles and beyond the same at both ends. At one end of the shaft is mounted a sprocket wheel 34 having a chain or belt connection 35 with a wheel 36 secured to the motor shaft 13, whereby the main drive shaft 33 is rotated. This wheel 34 may be clutched to the shaft by means of a clutch 37 of any suitable type, and adjacent to this clutch is another sprocket wheel 38 adapted to be secured to the shaft through a hand-operated clutch 39. From the wheel 38 there leads a conveyer drive chain or belt 40 to the wheel 41 secured to the shaft 42 at the joint of the conveyer, and to the other end of this shaft is secured a wheel 43 having a drive belt 44 leading to the sprocket wheel 45 carried at the head shaft 26 of the auxiliary section 25. By this means the conveyer is operated from the motor.

At the other end of the main driving shaft

are mounted other driving connections. 46 is a sprocket wheel, from which a chain 47 leads to a sprocket wheel 48 mounted upon a transverse shaft 49 journaled in the conveyer frame. On the opposite end of this shaft is fixed a sprocket wheel 50 from which is operated a sprocket chain 51. The wheel 46 is shown as being connected to the shaft through a clutch 52 made effective by a hand wheel 53 threaded upon the shaft. On the opposite side of the hand wheel is another clutch 54, through which the hand wheel, when operated in the opposite direction along the shaft, serves to secure another sprocket wheel 55 to the shaft. A sprocket 80 chain 56 leads from this wheel to a larger sprocket wheel 57 associated with one of the truck wheels, and whereby the truck will be transported along the track when the coal gathering means is not in operation. The 85 wheel 57 is secured either to the rear axle or to the wheel adjacent thereto and from the other end of the same axle, a chain 58 operating over gears 59 and 60 on both axles, causes both axles to rotate positively at the 90 same time.

The pedestals 32 above referred to in connection with the mounting of the main driving shaft are secured upon a bolster 61 which may be essentially duplicated adjacent to the rear end of the truck frame. These bolsters are each supported upon a rocker 62 in the nature of a curved rack rolling upon a straight rack 63 secured to the main truck frame 10. By this means the 100 conveyer frame is given free rocking movement for automatic leveling irrespective of the exact condition or contour of the main supporting track. The manner of mounting the conveyer frame upon the pedestals, furthermore, insures that the conveyer may be tilted into any desired position around the axis of the shaft 33 without interfering in any manner with the operation of the driving means associated with said shaft.

Among the principal features of novelty and importance in this machine is the construction of the gathering means for the loading end of the conveyer. The gathering means includes a substantially flat pan-like structure 64 whose front edge 65 is straight and lies in practice substantially flush with the ground and beneath the pile of coal. This pan 64 has a length transversely of the machine substantially as great as the 115 full width of the operation or of an extent materially greater than the widest portion of the machine otherwise. I therefore provide a hinged wing or section 66 at each end of the pan, the same being hinged at 67. 120 The axle of each pair of hinges together with the line of connection between the main portion of the pan and the hinged portion is parallel to the longer axis of the conveyer and lies substantially in the vertical plane 130

of the rail on that side of the machine. The framework of the pan portion includes a pair of brackets 68. Each wing 66 is secured to a bracket 68 and is adapted to swing therewith around the axis of the hinges 67 with respect to the main portion of the pan. The bracket 68 includes, in addition to the main backbone or rib portion, a plate 68' arranged in spaced parallel relation to the main portion of the bracket, see Figs. 4 and 5. The plate 68' and the main portion of the bracket are provided with bearing holes 69 and 70, the latter being fitted with a bushing 71, and in these bearing holes is journaled a shaft 72, having at one end a head 73 with a round shoulder 74 journaled in the hole 69. Adjacent to the round shoulder is a polygonal portion 75, upon which is fitted a worm gear 76. Next is formed a round reduced portion 77 journaled in the bushing 71 and then in turn is another polygonal portion 78 upon which is fitted one of the feeder wheels 79 in the nature of a star wheel having a series of substantially radial arms 80, each fitted with a claw or digger 81, having a point directed toward the direction of movement of the claw. Each claw is locked removably in place by means of a set screw 82, or its equivalent, extending through the arm on its rear side. 83 indicates a worm shaft to the opposite ends of which are secured a pair of right and left hand worms 84 and 85 meshing with the respective worm gears 76 and whereby the worm gears and the feeder wheels 79 are driven positively in opposite directions, or so that the arms of the wheels directed toward each other sweep over the pan rearwardly toward the conveyer. By this means the coal loosened by the diggers or claws and conveyed toward the center of the pan and thence rearwardly will be delivered through an opening 86 at the center of the rear portion of the pan directly upon the conveyer, where the material will be engaged by the flights 22 and thence carried rearwardly and dumped into the car. The shaft 83 is driven from the above described chain 51 through a sprocket gear 87.

50 The feeder wheels being fixed in position upon the shaft 72 and movable with the shafts and brackets 68 around the longitudinal axes of the hinges 67, always have a fixed position with respect to said brackets and hinges. As seen best in Fig. 6, the body of the pan 64 is cut away at 88 beneath the imperforate central body portion of each wheel 79 to provide a clearance for the bracket and worm wheel 76 to swing upwardly through the bottom of the pan to enable the feeder wheels and wing sections 66 to assume a vertical position, as indicated in Fig. 3. In normal operating position the feeder wheels lie closely over and parallel to the plane of the pan, where they are held

by gravity and the interlocking or intermeshing engagement between the worms and the worm gears 76, it being noted that the center of gravity of each of the feeder wheel structures lies between the axis of the hinges 70 and the center of the conveyer. When, however, the feeder wheels are tilted to their upright position, the center of gravity then is shifted to the outside of the axis of the hinges, rendering it easy for the feeder 75 wheels to be maintained in such position until the machine is again set for operation.

The worm shaft 83 is journaled in a pair of sliding blocks 89 mounted in guideways 90 on opposite sides of the conveyer frame 80 and closely adjacent to the inner ends of the worms. 91 indicates a pair of jack screws journaled in the rear ends of the guides 90 and held from endwise movement by means of collars 92. The front end of each jack 85 screw 91 is in threaded engagement with one of the slidable blocks 89 and the rear end of the screw is provided with a beveled gear 93. 94 indicates a crank shaft carrying a crank 95 at one end and having a pair of beveled gears 93' secured thereon and meshing in the same relation with the beveled gears 93. By rotation of this crank 95 and shaft 94, the blocks 89 are moved simultaneously in the same direction with the 95 shaft 83 and worms toward or from the worm gears 76. Thus by rotation of the crank in one direction, the worms are withdrawn from contact with the worm gears, setting the feeder wheel devices free to be 100 tilted to their upright position. When, however, they are returned from their upright position the movement of the crank in the opposite direction returns the worms into mesh with the worm gears at any desired 105 degree of tightness. At the back portion of the pan structure is located a stiffening member 96, having an opening 97 at its center through which the coal is conveyed. This stiffening member serves to brace the 110 main conveyer frame at this point, giving a more rigid support to the frame section to which the boxing for the shaft 67 is secured, and includes a transversely extending strong angle bar 98 bridging the opening 97. 115

I claim:

1. In a coal loader, the combination of a conveyer frame, an endless conveyer operating thereover, gathering means carried by the front end of the conveyer frame and 120 including a pan-like structure lying in a plane just above and parallel with the plane of action of the conveyer and having an opening over the receiving end of the conveyer, said pan-like structure including a 125 pair of end wings pivoted to swing around the main portion of the pan around axes parallel to the conveyer, a pair of feeder wheels carried by said wing structures and tilttable therewith around said axes, and 130

means to actuate both the conveyer and the feeder wheels simultaneously.

2. In a coal loader, the combination of a conveyer frame, an endless conveyer operating thereover along a certain plane, gathering means including a pan-like construction carried by the front end of the conveyer frame and lying in operation just over the plane of said conveyer, said pan construction including a pair of end wings pivoted to swing around axes parallel to the center line of the conveyer so as to occupy vertical planes when out of operation, a pair of feeder wheels journaled upon and carried by the respective wing structures, means to actuate the conveyer, and means to actuate the feeder wheels in opposite directions with their adjacent portions movable rearwardly over the pan toward the center of the conveyer.

3. In a coal loader, the combination with a frame, a conveyer operating over the frame, and power means to actuate the conveyer, of gathering means carried by the front end of the conveyer frame, said gathering means including a pan lying over the receiving end of the conveyer, a section of the pan being tiltable around an axis parallel to the conveyer, and a feeder wheel journaled upon said tilting section and tiltable therewith from horizontal to vertical position, and means to drive the feeder wheel when in relatively horizontal position from the aforesaid power means.

35 4. In a coal loader, the combination with a main support, power means thereon, a conveyer operating over said support, and means to actuate the conveyer from the power means, of gathering means carried

at the front end of the conveyer and including a pan-like structure having a central opening at its rear portion over the conveyer, and a pair of feeder wheels operating in opposite directions in the same plane over the pan and toward said opening, and means to actuate the feeder wheels from said power means, said actuating means including a pair of worm gears connected to the respective feeder wheels, a pair of worms meshing with the worm gears, and means to adjust the worms toward or from the worm gears.

5. In a coal loader, the combination with a conveyer frame, a conveyer operating thereover and means to actuate the conveyer, of gathering means for the conveyer comprising a pan-like structure arranged over and parallel to the receiving end of the conveyer and having an opening to deliver the coal upon the conveyer, said pan structure including opposite end wings, a pair of brackets carrying said wings and hinged to the main portion of the pan so as to swing with the wings into vertical planes for transportation, the center of gravity of the wing structures being outside of their axes when the wings are vertical, but inside or between the axes of the wings when in operative position, a pair of driving shafts journaled in said brackets, a worm gear mounted upon each drive shaft within a bracket, a feeder wheel mounted upon the upper end of each shaft, a pair of worms, means to adjust the worms into mesh with the worm gears when the worm gears are in operative position, and means to drive the worms.

DANIEL B. STAUFF.
